UNITED STATES PATENT OFFICE.

CHARLES WILLIAM JACKSON, OF DRACUT, MASSACHUSETTS.

HELICOPTER.

Application filed March 14, 1928. Serial No. 261,592.

The object of this invention is to provide a machine of the type indicated in which a propeller or propellers are employed for directing an air current downwardly in a 5 centrally located tube, duct, or air tunnel, and in which other propellers direct currents downwardly and toward the central air current, for the purpose of reducing the air pressure above the machine to a maximum 10 extent, and facilitate the lifting action due to the air pressure below.

A further object is to provide a special arrangement of air ducts, with their propellers, and to so arrange certain of the latter that 15 the tendency of the entire machine to rotate will be eliminated or avoided.

A further object is to provide for the forward drive, and for utilizing the propellers serving this purpose for guiding the 20 machine.

With the foregoing and other objects in view, the invention consists in the novel construction and arrangement of elements described, illustrated, and claimed, it being 25 understood that modifications may be made within the scope of the claims without departing from the spirit of the invention.

In the drawings forming part of this application—

30 Figure 1 shows the machine in vertical section;

Figure 2 is a side elevation;

Figure 3 is a top plan view.

In the construction of the device, I employ 35 a central tube, duct or tunnel 10 including an upper flared portion 11, and having communication with a main lower air chamber or air space 13, of which the upper wall is designated 14.

40 An annular fuel chamber or fuel tank is formed between the wall of duct 10 (or the wall 12) and the concentric wall 15, an upper element 16 closing this chamber, and it being assumed that the fuel is to be conducted to 45 fuel mixing devices in the usual manner.

Duct 10 houses an engine 17 shown conventionally, and upper and lower propellers 18 and 19 are assumed to have their blades deflected at different angles, lessening or 50 avoiding the tendency of the machine to rotate or spin, due to the action of the motor or engine. A similar plan may be carried out in mounting the other lifting propellers.

55 The outer tubes or ducts 20 are surrounded by fuel receptacles 21, and the discharge of

air from these ducts is toward the center, and toward the current created by the central propellers. The motors for the outer ducts are designated 24, and their propellers are shown at 25, the discharge openings being 60 designated 26. The driving propellers 27, 28, may also be controlled in the manner required to permit of guiding the machine in this manner, or by these means, by varying the relative speeds of the engines 30, 31. 65

The several air tubes, which may be assembled as shown in Figure 3, enter a main housing of which the side portions are shown in elevation in Figure 2, the housing as a whole being designated 32 and including a 70 lower annular element 33, to which the stay wires or rods 34 are connected. These elements are also secured near their upper ends as shown, and the air tubes are tied and braced by connecting element or elements 75 35.

A deck or platform 36 extends around the machine, and may be protected by railing 37, the deck being braced by elements such as 38, and being adapted for the construction of cabins thereon, if desired. 80

The purpose is to reduce the air pressure above the machine, and to direct the air currents approximately as described, in the lower central portion of the device, and the 85 direction of drive of the propellers mounted on vertical axes is subject to variation, as are other details, within the scope of the claims.

The air chamber below the central air 90 tube is to be of sufficient capacity to permit of receiving the air currents from the outer lifting propellers without causing any of the currents to retard or counteract the flow of other currents, and with this in view the 95 discharge from propellers 25 may be deflected downwardly by any suitable means or by so directing the ducts 20. For stabilizing purposes the propellers 25 may be driven at different speeds, varying the air pressure 100 above one side of the machine with reference to that above the other side thereof.

What I claim is—

1. In a helicopter, a supporting structure, a central vertical air tube mounted therein and having open ends, a propeller positioned to discharge air through said tube, a motor for driving the propeller, additional ducts mounted vertically and propellers therefor, motors for driving these propellers, said ad- 110

ditional ducts having portions thereof deflected to discharge air toward the current created within the central duct.

2. In a helicopter, a supporting structure, driving propellers mounted thereon and rotatable about horizontal axes, a central vertical air tube mounted within said structure, a propeller positioned to discharge air through said tube, a motor for driving the propeller, additional air tubes and propellers therefor, motors for driving these propellers, said additional tubes being deflected to discharge air toward the current created within the central tube.

3. In a helicopter, a supporting structure, 15 a central air duct mounted thereon, a propeller positioned to discharge air through said duct, a second propeller, having blades positioned at an angle with those of the propeller first named, and being movable about the 20 same axis of rotation, a motor for driving these propellers, additional air ducts and propellers therefor, motors for driving the propellers last named, and means associated with the additional ducts for directing air 25 currents in converging relation.

In testimony whereof I affix my signature.
CHARLES WILLIAM JACKSON.
